MULTIPLE SLIDE CONTROL FOR COUNTER TYPE ELECTRIC HEATERS

Roger L. Crispell, Birmingham, Mich., assignor to General Motors Corporation, Dayton, Ohio, a corporation of Delaware

Application February 10, 1955, Serial No. 34,454

Term of patent 7 years

(Cl. D81—10)

Fig. 1

Fig. 2

Figure 1 is a top view of a multiple slide control for counter type electric heaters embodying my new design;

Figure 2 is a perspective view showing the front, top and left side thereof; and

Figure 3 is a side view of the control.

The dominant features of my design reside in the portions shown in full lines.

Fig. 3

I claim:

The ornamental design for a multiple slide control for counter type electric heaters, as shown and described.
